ABSTRACT

The present invention relates to a multibeam antenna arrangement having minimal aberration of astigmatism and coma over a wide area of the focal surface of the antenna. The present antenna comprises a plurality of N reflectors arranged confocally in a sequence along a feed axis of the antenna and at least one feed disposed in the vicinity of a focal point on the focal surface. The reflectors and the at least one feed are further arranged to provide an equivalent centered antenna arrangement with the longitudinal axis of the feed corresponding to an equivalent axis of the centered arrangement for eliminating astigmatism. Coma is then eliminated by deforming two of the N reflectors in a predetermined manner.

**MULTIBEAM ANTENNA ARRANGEMENT WITH
MINIMAL ASTIGMATISM AND COMA**

**CROSS-REFERENCE TO RELATED
APPLICATION**

This application is a continuation-in-part of application Ser. No. 352,389 filed Feb. 25, 1982, abandoned.

BACKGROUND OF THE INVENTION

1. Field of the Invention

The present invention relates to aplanatic reflector arrangements for offset multibeam ground station or satellite antennas and, more particularly, to multibeam antenna arrangements comprising N reflectors disposed in a particular sequential arrangement with two of the reflectors being slightly deformed in a predetermined manner to cause substantial elimination of the aberrations of astigmatism and coma over a wide area of the 20 focal surface of the antenna.

2. Description of the Prior Art

Of considerable interest in practice is the problem of modifying an existing or a new antenna design so as to reduce or substantially eliminate aberrations which 25 might be produced. More particularly, Cassegrainian and Gregorian reflector arrangements are needed for multibeam ground station and satellite antennas. In these antennas, an arrangement of two reflectors, a paraboloid and either a hyperboloid or an ellipsoid, is combined with several feeds disposed in the vicinity of 30 a focal point. Each feed produces a beam whose direction is determined by the feed displacement from the focal point. This displacement has been found to normally cause aberrations due primarily to astigmatism and coma. Various arrangements have been derived to correct one or more of such aberrations in antennas. One such arrangement was for Spherical, Coma and 35 Chromatic Aberrations" by A. R. Panicali et al in *Proceedings of the IEEE*, Vol. 59, No. 1, February, 1971, at pp. 311-312 where a corrugated reflector with varying depths of corrugations was suggested.

In the article "Astigmatic Correction by a Deformable Subreflector" by W-Y Wong et al in *AP-S International Symposium*, Vol. II, Seattle, Wash., 1979, at pp. 706-709, a mechanically deformable subreflector is suggested for providing a first order astigmatic correction. Other astigmatic correction arrangements have been disclosed in, for example, U.S. Pat. No. 4,145,695 issued to M. J. Gans on Mar. 20, 1979 and U.S. Pat. No. 4,224,626 issued to R. L. Sternberg on Sept 23, 1980. The Gans patent provides an astigmatic launcher reflector for each off-axis feedhorn which has a reflector having a curvature and orientation of its two orthogonal principal planes of curvature which are chosen in accordance with specific relationships. The Sternberg patent uses a lens having an elliptical periphery and surfaces defined by a system of nonlinear partial differential equations.

U.S. Pat. No. 4,166,276 issued to C. Dragone on Aug. 28, 1979 relates to an offset antenna having improved symmetry in the radiation pattern and comprising a curved focusing main reflector, at least two conic subreflectors and a feedhorn, the combination of these elements being oriented such that the feedhorn is disposed at the focal point of the combined confocal reflectors and in a manner to coincide with the equivalent axis of

the antenna system. Such arrangement eliminates astigmatism to a first order approximation.

More recently, U.S. patent appln. Ser. No. 209,943 filed on Nov. 24, 1980 for T. Chu, now U.S. Pat. No. 4,339,757, and U.S. patent appln. Ser. No. 209,944 filed on Nov. 24, 1980 for E. A Ohm, now U.S. Pat. No. 4,343,004, where each disclose different astigmatic correction means comprising a first and a second doubly curved subreflector which are curved in orthogonal planes to permit the launching of an astigmatic beam of constant size and shape over a broadband range.

The foregoing astigmatic correction arrangements, however, are primarily designed to provide such correction in a very limited portion of the focal surface.

15 The problem remaining in the prior art is to provide an antenna arrangement for multibeam transmission which will correct for astigmatism and also coma over a wide area of the focal surface of the antenna arrangement.

SUMMARY OF THE INVENTION

The foregoing problem has been solved in accordance with the present invention which relates to aplanatic reflector arrangements for offset multibeam ground station or satellite antennas and, more particularly, to multibeam antenna arrangements comprising N reflectors disposed in a predetermined manner to cause substantial elimination of the aberrations of astigmatism and coma over a wide area of the focal surface of the antenna.

It is an aspect of the present invention to provide an offset antenna with astigmatism and coma free operation in the general area of a focal point and at substantially reduced values beyond such area by confocally arranging a plurality of N reflectors in sequence to provide an equivalent essentially centered antenna arrangement which is free of astigmatism, and doubly curving two of the reflectors in a predetermined manner to also eliminate coma.

Other and further aspects of the present invention will become apparent during the course of the following description and by reference to the accompanying drawings.

BRIEF DESCRIPTION OF THE DRAWINGS

Referring now to the drawings, in which like numerals represent like parts in the several views:

FIG. 1 is a typical prior art antenna system where a spherical wave from a focal point F_0 is transformed into a plane wave by three confocal reflectors;

FIG. 2 is a diagram of a method of determining the equivalent axis of a reflector via a reflected ray emanating from a foci of the reflector;

FIG. 3 illustrates the method of FIG. 2 extended to 55 determine the equivalent axis of a confocal sequence of N reflectors;

FIG. 4 illustrates a simple method for determining the equivalent axis of a sequence of N confocal reflectors where the last reflector, Σ_N , is a paraboloid in FIG. 3;

FIG. 5 is an exemplary illustrative antenna reflector arrangement including four ellipsoid reflectors for transforming an input ray into an output ray in accordance with the present invention;

FIG. 6 illustrates any one of the ellipsoids of FIG. 5 which is to be deformed as specified in the present invention; and

FIG. 7 illustrates a compact reflector arrangement in accordance with the present invention.

DETAILED DESCRIPTION

In accordance with the present invention, a multibeam antenna arrangement is provided which substantially eliminates the aberrations of astigmatism and coma. In the present arrangement, astigmatism is substantially eliminated for feeds in the vicinity of a focal point by centering the antenna aperture with respect to an equivalent paraboloid axis. Having achieved an effectively centered arrangement, coma is then substantially eliminated by doubly curving two of the reflecting surfaces of the antenna arrangement in a predetermined manner as will be explained hereinafter.

A preferred technique for achieving an effectively centered antenna arrangement in an offset antenna is described in U.S. Pat. No. 4,166,276 issued to C. Dragone on Aug. 28, 1979 and briefly discussed hereinbefore. In accordance with the patented arrangement, perfect performance in cross-polarization discrimination and elimination of astigmatism to a first order approximation is achieved in an antenna system by disposing a symmetrical feedhorn at the focal point of the antenna system such that the longitudinal axis of the feedhorn coincides with the equivalent axis of the antenna system. The description which follows is intended to provide the necessary background and explanation for the various arrangements of antenna elements to achieve a centered arrangement with astigmatism free operation in the far field of the antenna and is a condensed explanation of the patented Dragone arrangement.

In FIG. 1 a typical antenna system is shown comprising a feedhorn 10 disposed at a focal point F_0 of the antenna system and three reflectors designated Σ_1 and Σ_3 to produce a spherical wave after each reflection which passes through focal points F_1 and F_3 , respectively. Thus, in general, if F_N is the focal point after the Nth reflection, the Nth reflector Σ_N transforms a spherical wave centered at the focal point F_{N-1} , into a spherical wave centered at focal point F_N . It is to be understood that any of the focal points F_0 to F_N may be at ∞ , in which case the corresponding spherical waves become plane waves. This condition is shown in FIG. 1 by placing F_3 at ∞ which requires reflector Σ_3 to be a paraboloid.

It can be demonstrated that a sequence of confocal reflectors as shown, for example, in FIG. 1 always has an equivalent single reflector which will be either an ellipsoid, hyperboloid or paraboloid. This equivalent reflector produces, after a single reflection the same reflected wave pattern as was produced by the given sequence of reflectors. This means that the field distribution over a wavefront reflected by the equivalent single reflector will coincide with the field distribution over the corresponding wavefront produced by the given sequence of reflectors. It is to be understood that such equivalent single reflector does not necessarily coincide with the location of any one of the given sequence of reflectors or that the direction of the wavefront produced by the single equivalent reflector has to correspond to the direction of the wavefront produced by the given sequence of reflectors. The only correlation between the single equivalent reflector and the given sequence of reflectors is that the field distribution over the wavefront produced by each of the arrangements are the same.

In accordance with the foregoing explanations, for purposes of determining the properties of the reflected

wave, it is possible to replace the N confocal reflectors of FIG. 1 with an equivalent reflector (not shown). The equivalent reflector has an axis of revolution which passes through focal point F_0 and will hereinafter be referred to as the "equivalent axis". The equivalent axis for the three reflectors of FIG. 1 may, for example, be in the direction shown in FIG. 1. How the equivalent axis is determined will be more clearly shown hereinafter. It is to be understood that in order for the symmetry of the incident beam to be preserved, the principal ray 5 must coincide with the equivalent axis, where the principal ray is that ray which corresponds to the longitudinal axis of the feedhorn disposed at focal point F_0 . Since, in theory, it is possible to travel along the equivalent axis in two opposite directions, two opposite orientations can be chosen for the principal ray. Suffice it to say, that for symmetry to be preserved, and in turn to 10 eliminate cross-polarization components in the wavefront reflected by reflector Σ_3 in FIG. 1, feedhorn 10 should be reoriented to have its longitudinal axis coincide with the equivalent axis.

For a clear understanding of the definition and derivation of the equivalent axis, the single reflector Σ_1 as shown in FIG. 2 will be considered. If the reflector Σ_1 and one of its foci F_0 are known, but the exact location of the axis of Σ_1 is not known and must be found, then the following procedure may be used. A ray emanating from foci F_0 is reflected twice by Σ_1 as shown in FIG. 2 where the construction of the complete reflector Σ_1 is also shown. Where s and s'' are the initial and final direction of the ray, respectively, after two reflections by Σ_1 , then it can be seen that s will only equal s'' when the ray coincides with the axis of the reflector. Therefore, by searching for a ray which satisfies this condition, the axis of the reflector can be found. As can also be seen from FIG. 2, two such rays can satisfy the condition where $s=s''$, the one shown in the Figure and the one which emanates from F_0 in a direction opposite to that shown in FIG. 2 for the axial ray.

The previous description can also be extended to determine the equivalent axis for a confocal sequence of reflectors Σ_1 to Σ_N as shown in FIGS. 3 and 4 where $N=3$. This is possible since, as was stated previously, a confocal sequence of reflectors has an equivalent single reflector. Thus, to determine the equivalent axis of a confocal sequence of reflectors, a ray from focal point F_0 with a direction s must be reflected twice by each of the reflectors Σ_1 to Σ_N such that $s=s''$. The two reflections at each reflector indicates a total of $2N$ reflections in the original configuration and the first N reflections occur in the order $\Sigma_1, \dots, \Sigma_N$ while the last N reflections have the reverse order. The final ray has a direction s'' which is the same direction s as the original ray when the original ray was launched coincident with the equivalent axis of the confocal sequence of reflectors.

As shown in FIG. 3 $s=s''$ and, therefore, the ray through focal point F_0 gives the correct orientation of the equivalent axis and, in turn, the direction of the principal ray for which symmetry is preserved. More particularly, the path of the ray in FIG. 3 is closed after $2N$ reflections and will retrace the original path during each subsequent $2N$ reflections. This closed path, which determines the equivalent axis, will hereinafter be referred to as the "central path" and the two rays which proceed along the central path in opposite senses will be referred to as "central rays".

The condition that $s=s''$ leads to a straightforward geometrical procedure for determining the equivalent

axis when the Σ_N reflector is a paraboloid as shown in FIG. 4. In FIG. 4 it is shown that when the last reflector Σ_N is replaced by a concave paraboloid reflector in, for example, FIG. 3, the final ray direction after two reflections therefrom becomes independent of the initial direction towards the first reflection therefrom. Therefore, the final ray after the second reflection coincides with the paraboloid axis and has a direction going from focus F_{N-1} towards the vertex V of the paraboloid Σ_N .

Having substantially eliminated astigmatism with an equivalent centered antenna reflector arrangement, any phase error produced over the antenna aperture is a function of the aperture coordinate x,y and is due to coma aberration. This residual aberration can be reduced by increasing the equivalent focal length f. However, this would increase the feed dimensions, and also the separation between feeds corresponding to different beams in a multibeam antenna. In accordance with the present invention, coma is substantially eliminated without increasing the focal length, f, by slightly deforming two of the antenna reflectors. For the special case of a two reflector Cassegrainian or Gregorian antenna, both reflectors can be modified. Alternatively, the subreflector can be replaced with two deformed reflectors without modifying the main reflector, or the two reflector antennas can be combined with two additional deformed reflectors. Additionally, it is to be understood that two sequential reflectors need not be deformed, although permissible, but that any two of the N reflectors are deformed as outlined hereinafter no matter where in the sequence along the feed axis.

For a clear understanding of the necessary deformations of two of a sequence of N reflectors to overcome coma once a centered arrangement is achieved, an exemplary sequence of four reflectors, where $N=4$, will now be considered to primarily define terms used hereinafter in accordance with the present invention. In FIG. 5, reflectors 1-4 are arranged confocally where reflector 1 has a first focal point F_0 on the focal surface where, for example, feedhorn 10 of FIG. 1 would be disposed along the equivalent axis. A principal ray 50 emanating from first focal point F_0 is reflected at a central point I_1 on reflector 1 with an angle of incidence

will be described to substantially eliminate coma and provide an aplanatic arrangement. To achieve such aplanatic antenna arrangement using the exemplary arrangement of FIG. 5, it is to be understood that any two of such reflectors 1-4 can be deformed. FIG. 6 is used to define the deformation necessary for any of the two reflectors.

In FIG. 6, an nth reflector, representing any one of the two reflectors to be deformed, is shown having a first focal point F_{n-1} , a second focal point F_n , a central point on the reflector I_n , an angle of incidence $2i_n$ where the length F_{n-1} to I_n is designated l_{2n-2} and the length I_n to F_n is designated l_{2n-1} . If, for example, reflector 2 of FIG. 5 were to be deformed, then $n=2$ and in FIG. 6 $I_n=I_2$, $F_{n-1}=F_1$, $F_n=F_2$, $l_{2n-2}=l_2$ and $l_{2n-1}=l_3$, which corresponds to the elements associated with reflector 2 in FIG. 5. It is to be understood that in FIG. 6 both lengths are positive in value since both foci are disposed in front of the nth reflector. However, if one of the two foci is behind the reflector, then the corresponding length is negative.

The magnification of the nth reflector, M_n , is defined by

$$M_n = - \frac{l_{2n-2}}{l_{2n-1}}. \quad (1)$$

For purposes of illustration, it will be assumed that the nth reflector is derived from an ellipsoid or hyperboloid defined by the equation

$$z_n = z_n(x_n, y_n) + C_n(x_n^2 + y_n^2)^2, \quad (2)$$

where C_n is the coefficient of deformation of the nth reflector.

To determine the coefficient of deformation of a first and a second reflector of the sequence of reflectors the designations n_1 and n_2 will be used to represent the first and second deformed reflectors, respectively, hereinafter. Coma free operation in an equivalent centered antenna arrangement is accomplished by deforming n_1 and n_2 in accordance with the coefficients of deformation derived from the equation:

$$-\frac{C_{n_1} \cos^2 i_{n_1}}{(l_{2n_2-1})^4 C_{n_2} \cos^2 i_{n_2}} = \frac{2^5(M-1)}{\frac{(M_1 \dots M_{n_2})^2}{\sum_{s=0}^{n_2-n_1-1} \frac{l_{2(n_1+s)} + l_{2(n_1+s)-1}}{l_{2(n_1+s)} l_{2(n_1+s)-1}} (M_{n_1+s+1} \dots M_{n_2})^2}} \quad (3)$$

$2i_1$ and passes through second focal point F_1 of reflector 1. Focal point F_1 is also a focal point of reflector 2 and the principal ray 50 is reflected at a central point I_2 of reflector 2 with an angle of incidence $2i_2$ and passes through a second focal point F_2 of reflector 2, which second focal point F_2 is also a first focal point of reflector 3. The principal ray is similarly reflected by reflectors 3 and 4 and passes through the second focal point F_4 of reflector 4 which is the F_{N+1} focal point of the arrangement. The length F_0 to I_1 is designated l_0 , the length I_1 to F_1 is designated l_1 , the length F_1 to I_2 is designated l_2 and so forth with the length I_4 to F_4 being designated l_7 .

An optical system satisfying Abbe's sine condition as described in greater detail in the book *Principles of Optics*, by M. Born and E. Wolf, Pergamon, N.Y., 1959 in Section 4.10 at pages 197-200, is called aplanatic and is free of aberrations. In accordance with the present invention, two of N reflectors are slightly deformed as

where $(M_{n_1+1} \dots M_{n_2})$ represents the product of the magnifications of the reflectors n_1+1 to and including reflector n_2 ; M is the total magnification of the antenna arrangement; and $(M_1 \dots M_{n_2})$ is the product of the magnifications of the first reflector up to and including the n_2 reflector of the antenna arrangement.

Having thus substantially eliminated primary astigmatism and primary coma, any residual phase error produced over the antenna aperture by a feed placed in the vicinity of the focal point F_0 is very small since it can be shown to be proportional to the square of the distance d_f of the feed from the focus. In the vicinity of the center of the aperture, the residual phase error is due to astigmatism, with coefficient A_2 being proportional to d_f^2 . In general, if the various magnifications M_n which specify the distances l_{2n-2} and l_{2n-1} are chosen arbitrarily, a nonzero A_2 will be produced. It is,

however, possible to choose, in general, the magnifications M_n so as to cause A_2 to approximately equal 0. This is important in those applications requiring large displacements d_f . Of greatest interest is the case of two reflectors including a deformed subreflector and a deformed parabolic main reflector arranged with a common plane of symmetry. Then it is important to minimize A_2 when the feed displacement from the focus is orthogonal to the plane of symmetry since large feed displacements are possible in this case without blocking the aperture with the feed, or the subreflector whose dimensions must be increased when large feed displacements must be accommodated. For such an arrangement with d_f orthogonal to the symmetry plane, it can be shown that the residual coefficient A_2 can be made to vanish by choosing the subreflector magnification M_1 so that

$$M_1 = \frac{1}{1 + \tan i_1 \tan i_2} \frac{d}{l_2}, \quad (4)$$

20

where d is the distance $|I_1 I_2|$ between the two reflectors shown in FIG. 7. It is to be recalled that in order for primary astigmatism to be eliminated, the angles of incidence i_1 and i_2 must satisfy the condition

$$\tan i_2 = \frac{M_1 - 1}{M_1} (\tan i_1) \quad (5)$$

25

discussed in U.S. Pat. No. 4,166,276 issued to C. Dra- 30 gone on Aug. 28, 1979.

It is of interest in practice to satisfy condition (4) with a compact arrangement in which the distance between the two reflectors does not exceed appreciably the aperture diameter D . This can be obtained, without violating condition (5), and without blocking the aperture, only for certain values of the magnification M_1 . More precisely, one finds that M_1 must be closed to 0.5, in which case $\tan i_1$ and $\tan i_2$ have approximately the same magnitude, but opposite sign. By choosing, for example, $M_1=0.5$ and $2i_1 \sim 70$ degrees, the arrangement of FIG. 7 is obtained with $2i_2 \sim -70$ degrees, $d=0.509 l_1$ and $D=d$. The equivalent focal length f is only $0.980 \times D$, and therefore each feed has a relatively small aperture, and the feed displacement from the focus is small, for a given angular displacement $\delta\theta$ of the antenna beam from the axis.

This arrangement, because it is virtually free of aberrations for relatively large values of $\delta\theta$, is expected to be particularly useful for ground stations with a wide 50 field of view, exceeding for instance ± 10 degrees. The field of view obtainable in FIG. 7 is expected to be comparable to that of the well-known Schmidt camera.

What is claimed is:

1. A multibeam antenna arrangement with minimal 55 aberrations due to astigmatism and coma, comprising: a plurality of N sequentially confocal reflectors including $N+1$ separate focal points comprising at least a curved focusing offset main reflector capable of bidirectionally reflecting a beam of radiated electromagnetic energy 60 between the Nth and the $N+1$ focal points along a feed axis thereof, and a subreflector disposed along the feed axis of the main reflector comprising a curved reflecting surface capable of bidirectionally reflecting said beam between said N^{th} and an $N-1$ points of the $N+1$ separate focal points; and

at least one feedhorn disposed at or in the vicinity of a first focal point of said $N+1$ focal points and

oriented with a longitudinal axis thereof coincident with an equivalent axis of the plurality of N sequential confocal reflectors, the equivalent axis being an axis of revolution which passes through the first focal point of an equivalent reflecting surface which is capable of producing after a single reflection the same field distribution over the reflected wavefront as that of the plurality of N sequential confocal reflectors

characterized in that

the reflecting surface of each of two of the plurality of N sequential confocal reflectors are deformed with a separate deformation coefficient, C_n specifying the displacement, Z_n , of each associated reflecting surface in the Zth direction according to the relationship

$$Z_n = C_n P_n$$

where P_n is the distance from the Z axis at a focal point of the reflector, and the deformation coefficient for each of the two reflecting surfaces is specified by the relationship

$$-l_{2n-1} C_{n2} \cos^{2i_{n2}} = (l_{2n-1}^2 \frac{C_{n1} \cos^{2i_{n1}}}{(M_{n1+1} \dots M_{n2})^4}) = \frac{2^5 (M-1)}{(M_1 \dots M_{n2})^2 \sum_{s=0}^{n_2-n_1-1} \frac{l_{2(n_1+s)+l_{2(n_1+s-1)}}}{l_{2(n_1+s)}^2 (M_{n1+s+1} \dots M_{n2})^2}}$$

where the magnification of any reflector

$$M_n = \frac{l_{2n-2}}{l_{2n-1}}$$

with l_{2n-1} and l_{2n-2} being the distances along the feed axis of the antenna arrangement to a central point on the reflector from the focal point of the reflector nearest and furthest, respectively, from the first focal point of the antenna arrangement; n_1 and n_2 designate the number of the nearest and furthest reflector, respectively, along the feed axis from the first focal point of the antenna arrangement to be deformed; i is the angle of incidence of a ray propagating between the two focal points of a reflector which impinges the central point of the reflector n ; $(M_{n1+1} \dots M_{n2})$ represents the product of the magnifications of the reflectors n_1+1 to and including reflector n_2 ; M is the total magnification of the antenna arrangement; and $(M_1 \dots M_{n2})$ is the product of the magnifications of the first reflector up to and including the n_2 reflector of the antenna arrangement.

2. A multibeam antenna arrangement according to claim 1 wherein $N=2$ and each of the two reflectors is deformed in accordance with its predetermined deformation coefficient.

3. A multibeam antenna arrangement according to claim 2 wherein the two reflectors comprise a deformed parabolic main reflector and a deformed subreflector and the magnification, M_1 , of the subreflector is defined by

4,503,435

9

$$M_1 = \frac{1}{1 + (\tan i_1)(\tan i_2)} - \frac{d}{l_2}$$

where i_1 is the angle of incidence of a ray impinging a central point on the reflecting surface of the subreflec-

10

tor, i_2 is the angle of incidence of the ray impinging a central point on the reflecting surface on the main reflector, d is the distance between the central points on the reflecting surfaces of the main reflector and subreflector, and l_2 is the focal length of the main reflector.
